MINING MACHINE

John Connel Sproul, Glasgow, Scotland, assignor to Mavor & Coulson, Limited, Glasgow, Scotland

Application February 25, 1950, Serial No. 146,183

5 Claims. (Cl. 262—8)

1

This invention relates to machines for mining coal or other mineral and belonging to a previously proposed type having a cutter head adapted to strip off the mineral in the advance of the machine by wedging or splitting the mineral along a more or less vertical plane. Where, as is usually desirable, the machine is double-ended—that is to say, is designed to work in each of its two directions of travel—there are two such cutter heads.

In machines of the type stated, a cutter head has one or more wedge-like face cutters which perform the main vertical-plane cutting operation on the seam, and a floor cutter in the form of a horizontal-edge wedge for removing the mineral from the floor. Such a floor cutter is usually formed or associated with a sloping ramp for lifting and deflecting sidewise the mineral shovelled from the floor. A cutter head may also include a horizontal-edged roof cutter, which would be arranged directly above the floor cutter.

Machines of the type stated are subjected to serious difficulties due to the seriously varying nature of coal and other mineral seams, the extremely restricted nature of the space in which the machine must work and the irregularities of the floor and roof surfaces of mines.

In accordance with the present invention, a mining machine of the type stated has a cutter head which is connected to the frame of the machine so as to be tiltable sidewise in relation to its normal working position under heavy reactionary forces and which is associated with means acting to maintain it in said position.

The means of connection may be such that the cutter head is turnable about a longitudinal axis.

The means acting to maintain the cutter head in its normal working position may be powerful centralising springs.

Where the machine is double-ended, each cutter head may have locking means for holding it rigid when it is the trailing head—that is, the cutter head out of use for the time being.

A machine of the before-mentioned type, designed for mining coal, is shown by way of example in the accompanying drawings to illustrate the invention. In the drawings, Figs. 1 and 2 are a diagrammatic side elevation and a plan of the machine. Fig. 3 is a fragmentary section of the cutter head, drawn to a much larger scale, approximately on the line 3 of Fig. 2. Fig. 4 is a sectional elevation, the section being on the line 4—4 of Fig. 1 and being drawn to a larger scale.

2

The general arrangement of the mining machine to which the invention is shown applied is drawn in simple outline in Figs. 1 and 2, the construction and operation of the machine in general not being material to the present invention. In order that the relationship of the invention to the machine can be adequately understood, the following brief description of the machine is given.

10 The machine shown is double-ended, comprising mainly a frame like body 7, 8, 9 and 10, a carriage 11 and two cutter heads 12 and 13. The body consists of two transverse end walls 7 and 8, to which the heads are connected, and two longitudinal guide bars 9 and 10, on which the carriage is slidably mounted. As will be obvious from Fig. 1 the structures forming the heads 12 and 13 rest upon the mine floor and bear the weight of the entire machine. The framewise body 7—10 is located between the two heads and is supported by them clear of the mine floor.

15 The carriage incorporates hydraulic propulsion apparatus. This apparatus includes a vertical hydraulic jack consisting of a cylinder 14 with a foot 15, the cylinder being vertically movable in a holder 16 incorporated in the carriage, and a piston-operated head 17 which normally rests upon the holder. The propulsion apparatus also includes a hydraulic ram unit consisting of a horizontal cylinder 18 and a ram 19 extending from both ends of the cylinder and engageable at its ends with the walls 7 and 8.

20 In order that the machine shall be propelled say from left to right (as viewed in Figs. 1 and 2) 25 the jack is operated firstly to depress its foot 15 against the floor of the mine and secondly to lift its head 17 against the mine roof. The jack thus extended provides a securely anchored abutment. Next the ram unit is operated so 30 that the ram 19 is forced to the right, the ram thus engaging the wall 8 and pushing the frame-like body 7—10, with the head 13 leading, upon the mine floor towards the right, the guide bars 9, 10 sliding through the now stationary carriage 35 11 and the heads 12 and 13 sliding over the mine floor. Thus, the head 13 performs its cutting stroke. Thereafter, the jack is operated so that its head is lowered and its foot raised, thus contracting the jack and freeing it from the roof and 40 floor. Finally, the ram unit is operated so that the ram 19 is forced to the left, the ram thus engaging the rear wall 7 so that the carriage 11 is pushed to the right. The carriage freely slides to the right hand end of the guide bars 9, 10 to 45 50 take up a new position of anchorage for the next 55

cutting stroke. This completes the cycle of operations.

Both cutter heads 12 and 13 are of similar construction. Therefore only one of the heads, namely the right hand head 13, is hereinafter described.

In the example, the cutter head comprises a leading cutter 20 at an intermediate level, two cutters 21 and 22 above the cutter 20, a floor cutter 23 and a roof cutter 24.

Each of the main cutters 20, 21, 22 and 23 is an edged plate that is attached to an approximately wedge-like body, the bodies being indicated by 25, 26, 27 and 28 respectively. The cutter head includes a heavy casing 29 in which the bodies 25-28 are all pivotally mounted.

The casing 29 is attached by a joint 30 to the adjacent end wall 8 of the framelike body 7-10 of the machine. The joint 30 is a circular flange with a concentric circular protruding spigot 31. The flange being secured by screws 32 to the casing 29 of the adjacent cutter head and fitting into a recess 33 in the adjacent end wall 8. The spigot engages in a bearing 34 in the casing 29. The axis X-X (Fig. 3) of the circular joint 30 formations, namely the male formations 30, 31 and the female formations 33, 34, is horizontal and extends longitudinally of the machine, being parallel to the axis of the guides 9, 10.

The casing 29, at opposite upper corners, has two small laterally spaced housings 35 in which are fitted plungers 36, the feet of which are pressed downwards by powerful springs 37 against the top face 38 of the adjacent end wall 8. The pressure of the springs is adjustable by screw stops 39 against which they react. These springs, by pressing in opposition to one another with reference to the axis X-X, strive to maintain the cutter head in its central position, in which the bottom of the head occupies a plane parallel to the foot 15 of the jack 14-17 and which is its normal working position. Under excessive turning force applied to the head, one of the springs is heavily compressed and yields, thus permitting the head to tilt sidewise in relation to its normal working position. In the example, the sidewise tilting consists in turning of the head about the longitudinal axis X-X of the joint 30-34 the extent of such turning is limited to the small extent permitted by the associated screw stop 39.

The cutter head also is provided with a bolt 40 for locking it rigidly in central position to the adjacent end wall 8 of the frame. As shown in Fig. 3, the bolt 40 is mounted in a small housing 41 secured to the top of the wall 8, the bolt being in register with a hole 42 in the casing 29 whenever the cutter head is in its central position. The bolt is formed with a worm 43 and a square head 44 for turning it. A pin 45 screwed through the housing 41 engages the worm. The arrangement is such that, by turning the head 44, the operator can move the locking bolt into or out of locking engagement with the hole 42.

In use of the machine, assuming that it has to work from left to right as viewed in Figs. 1 and 2, the trailing cutter head 12 is locked by its locking bolt 40 (not shown in the drawings) and the leading (or working) cutter head 13 is left unlocked in its central position (as shown in Figs. 3 and 4). In the advance of the machine, any of various variations from normal conditions may be met. For instance, as the cutter head cuts a new face A from the seam B, the nature of the coal being stripped may become such that one of

the cutters 21 to 24 tends to cut deeper into the seam; and this tendency would impose a torque on the cutter head about the longitudinal axis X-X of the joint 30-34. Alternatively, the floor of the mine might be inclined locally upwards to the right or the left, thus pressing upwards on one or other side of the floor cutter 23 and imposing a torque on the cutter head. By virtue of the joint 30-34, the head can turn against the yielding opposition due to the combined action of the spring plungers 36; and the machine frame 7-10 itself is saved from tilting and other effects of excessive torsional stresses.

I claim:

1. A double-ended mining machine of the type stated having a longitudinal frame, a pair of cutter-carrying heads to bear upon a mine floor in order to support the weight of the machine, one of said heads being at the leading end of said frame and one at the trailing end thereof, that cutter head which for the time being is at the leading end being arranged when occupying its normal working position to cut mineral from a seam in an approximately vertical plane at one side of the machine, a connection between each of said heads and said frame, both connections having a longitudinal axis and each head, when free to do so, being tiltable sidewise out of its normal working position by turning about said axis, yieldable pressure means mounted on each cutter head and pressing against an adjacent end of said frame, the pressure being directed to maintain the head concerned in its normal working position, and locking means between the frame and each cutter head for holding against sidewise tilting that cutter head which for the time being is at the trailing end.

2. A mining machine of the type stated having a longitudinal frame component, a cutter-carrying head component to bear upon a mine floor in order to support the weight of the machine at the leading end of said frame component, said head component being arranged when occupying its normal working position to cut mineral from a seam in an approximately vertical plane at one side of the machine, a connection between said head and frame components such that the head component is tiltable sidewise in relation to its normal working position by heavy forces reactionary to the work of the cutter head component and the weight of the machine, and yieldable pressure means mounted on one of said components and pressing against the other of said components to maintain the head component in its normal working position but yielding due to sidewise tilting of the head component when subjected to excessive reactionary force.

3. A mining machine according to claim 2 in which the yieldable pressure means consists of compression spring means.

4. A mining machine of the type stated having a longitudinal frame component, a cutter-carrying head component to bear upon a mine floor in order to support the weight of the machine at the leading end of said frame component, said head component being arranged when occupying its normal working position to cut mineral from a seam in an approximately vertical plane at one side of the machine, a connection consisting of circular male-and-female formations between said head and frame components, said formations having a central longitudinal axis and said head component being tiltable sidewise out of its normal working position, by turning about said axis, under heavy forces reactionary to the work

of the cutter head component and the weight of the machine, and a pair of yieldable pressure devices mounted on one of said components and pressing in opposition to one another upon the other of said components to maintain the head component in its normal working position but either of them yielding due to turning of the head component about said axis when subjected to excessive reactionary force.

5. A mining machine according to claim 4 in which the yieldable pressure devices comprise

powerful centralising compression springs spaced apart on one of said components to exert opposed turning forces on the other of said components.

JOHN CONNEL SPROUL.
